Filed Jan. 31, 1969, Ser. No. 15,582

Term of patent 14 years

Int. Cl. D26—04

U.S. Cl. D48—24

FIG. 1

FIG. 2

Des. 217,926

PAGE 2

FIG. 3

FIG. 4

FIG. 5

FIG. 6

FIG. 1 is a front elevation view of the light unit;
FIG. 2 is a rear elevation view of the light unit;
FIG. 3 is a side elevation view of the light unit as seen from the right of FIG. 1;

FIG. 4 is a bottom plan view of the light unit;
FIG. 5 is a side elevation view of the light unit as seen from the left of FIG. 1; and
FIG. 6 is a top plan view of the light unit.

The lamp lens is shown in broken lines in FIGS. 1, 2, 3, 5 and 6 for illustrative purposes only.

We claim:

The ornamental design for a housing for a portable light unit, as shown and described.
